UNITED STATES PATENT OFFICE.

AARON DANGLO AND LOUIS RESCH, OF NEW YORK, N. Y.

WINDOW-SHADE FIXTURE.

1,083,807.

Specification of Letters Patent.

Patented Jan. 6, 1914.

Application filed July 11, 1913. Serial No. 778,457.

To all whom it may concern:

Be it known that we, AARON DANGLO, a citizen of the United States, and a resident of the city of New York, borough of Brooklyn, in the county of Kings and State of New York, and LOUIS RESCH, a citizen of the United States, and a resident of the city of New York, Bay Ridge, borough of Brooklyn, in the county of Kings and State 10 of New York, have invented a new and Improved Window-Shade Fixture, of which the following is a full, clear, and exact description.

Among the principal objects which the 15 present invention has in view are to provide retainers for the edges of window shades to normally hold the shade in desired position; to provide means whereby if the shade is forced out of normal or correct position, the 20 same may be returned without further damage to the fabric thereof; and to provide fixtures of the character named of simple and economical construction.

Reference is to be had to the accompanying 25 drawings forming a part of this specification, in which similar characters of reference indicate corresponding parts.

Figure 1 is an elevational view of fragments of a window, having a shade guided 30 and controlled by a fixture constructed and arranged in accordance with the present invention; Fig. 2 is a detailed view on an enlarged scale and in horizontal section, the section being taken on the line 2—2 in Fig. 35 3; and Fig. 3 is an enlarged detailed view in elevation, showing the fragment of a window frame and the upper and lower ends of the present fixture, the body thereof being parted and contracted.

40 The present invention relates to an improvement upon the structure disclosed in a patent for improvements in window shade fixtures, bearing No. 1,068,222, dated July 22, 1913, to which patent cross reference is here 45 made.

As seen in the accompanying drawings a semi-tubular guard fixture 12 is provided with a nailing flange 13, by which it is secured to the window frame and to a stop bead thereof. The guard fixture 12 is slotted longitudinally to guide the shank of the 50 guide pins 24, one of which pins are secured in each end of the slat 11, to which the hem is sewed.

55 As seen in the accompanying drawings,

the fixture 12 extends lengthwise and vertically at the side of the window opening. The shade 9 is cut to pass between the two fixtures 12, the edges of the said shade being adapted to rest in front of the swinging 60 flange 25, which is pivotally mounted upon the lip 18. The lip 18 and the swinging flange 25 are each provided with inter-leaved knuckles 26.

To form a hinge for uniting the flange 25 65 and lip 18, a spring wire 27, preferably constructed from piano wire is extended lengthwise through the said knuckles when interleaved and the ends 28 of the said wire are bent at right angles. The ends extend over 70 and engage the pins 29, one of which pins is formed on the lips 18, the other of said pins being formed on the flanges 25. The ends 28 are normally set in parallel relation, whereby the lip and flange are normally held 75 in straight line or parallel relation.

When the shade 9 is forced inward past the flanges 25 by a gust of wind or other cause, the same is readily and quickly replaced by grasping and turning backward 80 the flange 25 until the edge of the shade passes between the said flanges to its normal position. When the flange is being released the spring ends 28 move the same into holding or guiding relation to the said shade. 85

Claims—

1. A window shade fixture, comprising a guide member for a shade slat; a flange pivotally mounted upon said guide member to overlie the window shade; and a hinge pin 90 pivotally uniting said guide member and flange, said pin being constructed from spring metal, the ends thereof being overturned to engage said flange and said guide member to maintain the normal relation 95 thereof.

2. A window shade fixture, comprising a plurality of tubular guide members having open ends; a window shade having a slat extending between said guide members, headed pins mounted upon said slat, the heads of said pins extending within, to be held by said guide members; and a swinging flange pivotally mounted upon said guide members 100 to overlie said shade. 105

3. A window shade fixture, comprising a plurality of tubular guide members having open ends; a window shade having a slat extending between said guide members; headed pins mounted upon said slat, the heads of 110

said pins extending within, to be held by said
guide members, a swinging flange pivotally
mounted upon said guide members to overlie
said shade; and springs to hold said swing-
5 ing flanges in normally guiding relation to
said shade.

In testimony whereof we have signed our

names to this specification in the presence of
two subscribing witnesses.

AARON DANGLO.
LOUIS RESCH.
